Primary Examiner — David Muller(74) *Attorney, Agent, or Firm* — Manuel F. de la Cerra**CLAIM**

The ornamental design for a hand-held carry vise, as shown and described.

DESCRIPTION

FIG. 1 is a front left perspective view of the hand-held carry vise.

FIG. 2 is a front right perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken line showing of parts of the drawings is included for the purpose of illustrating use and environment and forms no part of the claimed design.
